SHOE HEEL

David Giesser, Chelsea, Mass.

Application October 27, 1941, Serial No. 416,702

1 Claim. (Cl. 36—34)

My invention relates to new and useful improvements in shoe heels.

An important object of my invention is the provision of a unique shoe heel assembly which will permit transparent heels to be applied to the shoe and which will prevent the nails or screws attaching the heel to the shoe from being visible.

Another object of my invention is the provision of a device of the above mentioned character wherein the heels are easily removable from the shoe, thus permitting substitute heels of various colors to be used.

Other objects and advantages of my invention will be apparent during the course of the following description.

In the drawing, forming a part of this specification, and wherein like numerals are employed to designate like parts throughout the same,

Figure 1 is a side elevation of a heel embodying my invention and showing the same applied to a conventional shoe or slipper.

Figure 2 is a front elevation of the heel.

Figure 3 is a vertical sectional view taken on the line 3—3 of Figure 2.

Figure 4 is a transverse sectional view taken on the line 4—4 of Figure 3, and

Figure 5 is a plan view showing the rod which holds the heel and insert portions of my invention together, parts being broken away for clearness of illustration.

In the accompanying drawing, wherein for the purpose of illustration, is shown a preferred embodiment of my invention, the numeral 10 designates the heel portion of a conventional shoe or slipper. My invention relates particularly to ladies' shoes although it is to be understood that my arrangement has other applications and that I do not wish to limit the invention in any way to ladies' shoes. It is the custom at the present time to attach molded or cast plastic heels to shoes, which heels are of varying colors and varying degree of transparency. Experience teaches that the heels may be best attached to the shoe by means of nails which are driven downwardly through the heel portion of the shoe and into the top of the heel. Such substitute means of attaching the heels to the shoe, as by glueing, have proven to be unsuccessful and decidedly inferior to the conventional manner of nailing the heel to the shoe. There are, however, difficulties attendant upon nailing the heel to the shoe. For instance, if the heel is relatively transparent the nails may be easily seen through the transparent material of the heel. I have therefore provided

a construction which performs the two-fold function of detachably or removably associating the heel with the shoe and of efficaciously preventing the nails which attach the same to the shoe from being visible.

The heel 11 is a heel of the above mentioned character, the same being made of a suitable transparent or translucent plastic material. For attaching the heel to the shoe 10 I have provided an insert 12 of opaque material having a flat bottom surface 14, a slightly concave top surface 13, a transverse front edge 15 and spaced parallel side edges 16 and 17 which curve inwardly at the rearward end of the insert to provide 10 the arcuately curved rearward end 18. Attention is directed to the fact that the side and rear edges of the insert slope outwardly from the upper and lower faces thereof to provide a medial ridge therearound.

15 The top surface 19 of the heel is provided with a recess 20 shaped to receive the insert 12. The recess opens through the front of the heel and conforms in plan and in front elevation with the shape of the insert. Figure 4 best illustrates the 20 manner in which the insert is received within the recess and the manner in which the outwardly convergent side and rear edges of the insert interlock with the correspondingly shaped side walls of the recess to efficaciously prevent 25 the heel from dropping from the insert. If the heel is to be removed from the insert it must be slidably moved in the direction of the arrow in 30 Figure 4 and it may only be applied to the insert by moving the same in a direction opposed 35 to the arrow.

I normally hold the heel fixedly associated with the insert by means of a rod 22 which extends transversely through aligning passages in the heel and insert adjacent the forward edge thereof.

40 When the front edge of the insert has been moved into register with the front surface 21 of the heel the passages 23 in the heel will register with the 45 passages 24 in the insert to permit the rod 22 to be slipped therethrough. The rod extends entirely through the passage 24 and the opposite ends thereof are received within the passages 23 of the heel. The ends of the rod terminate short of the sides of the heel and screws 25 are 50 inserted through the sides of the heel and screwed threadably received within sockets 26 in the ends of the rod. I prefer that a washer 27 be interposed between the head of the screw and the end of the rod which washer may be of plastic or felt or other suitable material to prevent the

head of the screw from chewing or digging into the sides of the heel.

When it is desired to remove the heel from the insert after the same has been nailed to the shoe, it is only necessary to move the screws 25 and to slip the rod 22 through the passages 23 and 24. The heel may be easily removed from the insert and another or a different color heel applied thereto. It will, of course, be necessary that the insert and heel be made according to standard specifications so that the passages therein will align with each other to accommodate the rod 22. If this relationship exists between the insert and the heel, the rod 22 may be used to attach any heel to the insert and it is therefore possible that a great many heels of varying colors may be interchangeably used with a single pair of shoes.

If desired the lower end portion of the heel may be provided with a recess 28 which opens through the bottom of the heel and is closed by

the rubber tip 29. A suitable coloring matter may be introduced into the recess 28 to add to the aesthetic appeal of the heel.

It is to be understood that the form of my invention, herewith shown and described, is to be taken as a preferred example of the same, and that various changes in size, shape and arrangement of parts may be resorted to without departing from the spirit of my invention or the scope 10 of the appended claim.

Having thus described my invention, I claim:

A shoe heel comprising a transparent body having a channel in its top surface, said channel having upwardly tapering side walls and opening through the front of the body, an opaque insert shaped to fit the channel slidably disposed therein, a rod extending through the body and insert from side to side, and screw threaded members received in sockets provided in the ends 15 of the rod.

DAVID GIESSER.
